UNITED STATES PATENT OFFICE.

FREDERICK C. FROELICH, OF PHILADELPHIA, PENNSYLVANIA.

AIR PUMP.

Original application filed November 23, 1922, Serial No. 602,704. Divided and this application filed March 18, 1924. Serial No. 699,973.

To all whom it may concern:

Be it known that I, FREDERICK C. FROELICH, a citizen of the United States, residing in the city and county of Philadelphia, State of Pennsylvania, have invented a new and useful Air Pump, of which the following is a specification, the same being a division of my application Serial No. 602,704, filed November 23, 1922.

10 My invention relates to an air pump and consists of barrels, pistons therein, air inlet valves and air outlet valves, and means for operating said pistons by the action of a cam or cam body whereby air in large volumes may be drawn into the barrels and in a measure compressed therein and then forcibly discharged therefrom in continuous flow to a place of service.

The invention is illustrated in the accompanying drawing, but the important instrumentalities thereof may be varied, and so it is to be understood that the invention is not limited to the specific details shown and described, as long as they are within the spirit or scope of the claims.

Figure 1 represents a longitudinal section of an air pump on line 1—1 Figure 2, embodying my invention.

Figure 2 represents a transverse section 30 thereof on line 2—2 Figure 1 on a reduced scale.

Figure 3 represents a transverse section thereof on line 3—3 Figure 1.

Figure 4 represents a side elevation of 35 the cam or cam body detached.

Figure 5 represents a section thereof on line 5—5 Figure 4.

Figure 6 represents a transverse section of 40 the housing of the pump detached from position.

Figure 7 represents a longitudinal section of another embodiment of the invention on line 7—7 Figure 8.

Figure 8 represents a transverse section 45 thereof on line 8—8 Figure 7, on a reduced scale.

Figure 9 represents a transverse section thereof on line 9—9 Figure 7, on a reduced scale.

Figure 10 represents a side elevation of 50 the cam or cam body detached from Figure 7 on the scale of Figures 8 and 9.

Similar numerals of reference indicate corresponding parts in the figures.

Referring to the drawings:

1 designates a housing formed of a casting which is surrounded by the inclosing casing 2, the forward end of which is secured to the flange 3 on the corresponding end of the housing by screws which are passed through said casing into said flange. In said housing are chambers forming a series of longitudinally extending barrels 4 which extend in circular form around said housing, and receive the pump pistons 5 which are movable in said barrels. Projecting from said flange 3 is the neck 6 which is hollow forming continuations 7 of the chambers of the barrels, the pistons being shorter than the entire lengths of the barrels so that they may have sufficient throws therein in opposite directions.

In the outer walls 8 of the barrels for a portion of the length thereof within the casing 2 are the longitudinally extending slots 9 in which are received the rollers 10 which are mounted on the pins 11 secured to the pistons and extending transversely through the pistons and are outturned to the exterior of the same where they have said rollers 10 secured in them. Surrounding the barrels 4 within the casing 2 is what I term the rotatable cam 12 which consists of a cup-shaped body having one end closed by the wall 13, and the opposite end open, said wall having thereon the hub 14 which is firmly connected with the shaft 15, the latter passing through the central opening 16 in the housing 1 as its bearings.

On the end of the housing opposite to the casing 2 is the head 17 which is cast with the housing and is hollow forming the air discharging chamber 18, the inner wall 19 of which has therein the series of ports 20 which are in communication with the barrels 4 respectively, the walls of said ports forming seats for the ball or other valves 21 which are adapted to open outwardly into or towards the chamber 18 so that air pumped into the barrels may be discharged therefrom into the chamber 18, the head having connected with it on its exterior the nozzle 22 which is in communication with the chamber 18 and adapted to direct the air to a place of service.

The valves 21 are held to their seats by the engaging coil or other springs 23 which occupy the chamber 18 and are connected

with and held in place by the plugs 24 which are screwed to the outer wall of the head 17.

In the neck 6 are the ports 25 one for each barrel, the same being in communication with the interior of the barrels respectively and with the interior of the plugs 26 whose bodies are screwed to the collars 27 on the neck 6 and in which are chambers for the 10 inwardly opening ball or other valves 28, the seats of the latter being on the bases of the air inlet ports 29 in said plugs. Said valves 28 when in closed positions are held on their seats by the springs 30 which rest 15 upon the adjacent portions of the necks 6 and bear against said valves 28.

In the inner face of the side wall of the cam or cam body 12 is the spiral groove 31 in which are received portions of the rollers 20 10 carried by the pins 11 on the pistons 5 as has been stated.

The operation is as follows:

Power is communicated to the shaft 15 of the pump in any suitable manner, thus rotating the cam 12 whereby the rollers 10 which are engaged in the spiral groove 31 and the pins 11 which are attached to the pistons 5 cause the latter to be reciprocated in the barrels. In one throw of the pistons 30 which in the present case is to the right, open the valves 28 and close the valves 21. Air is thus drawn in large volumes into the barrels through the ports 29 and 25 following the throw of the pistons. Then the piston returns making the opposite throw when the valves 28 are forced on their seats and open into the chamber 18 when the air is forcibly injected into the latter and from thence directed by the nozzles 22 to a place 35 of service, there being a continuous flow of air from the pump with great pressure.

In Figures 7, 8, 9 and 10 which show another embodiment of my invention, the cam or cam body is of the form of the collar 32 having thereon hubs 33 which are secured to an operating shaft similar to the shaft 15 in the prior figures, but the exterior surface of the collar has therein the spiral groove 34 to receive the rollers 35 which are secured to the ends of the pins 11 which are extended inwardly from the pistons 5, but the operation of the pump in this instance is similar to that shown and described in Figures 1-5 inc. Referring to 40 Figure 7 on the exterior of the housing 1 is a series of ribs 36 radiating from said housing and separated from each other forming surfaces beyond said housing adapted to cool said housing.

60 The pump in either case will be found admirably adapted for the purpose of inflating tires and other services in garages to which uses however, I do not limit myself.

It will now be apparent that I have devised a novel and useful construction of air

pumps which embodies the features of advantage enumerated as desirable in the statement of the invention and the above description, and while I have, in the present instance, shown and described preferred embodiments thereof which will give in practice satisfactory and reliable results, it is to be understood that the same are susceptible of modification in various particulars without departing from the spirit or scope 75 of the invention or sacrificing any of its advantages.

Having this described my invention, what I claim as new and desire to secure by Letters Patent, is:

1. An air pump comprising in combination, a horizontally arranged housing having a central cylinder casing, concentrically arranged cylinders each having a vertically arranged valved inlet and a horizontally arranged valved outlet at the same end thereof and having an elongated, horizontally disposed slot at the other end, a piston within each cylinder, a hollow cam operative for rotation around said cylinders said cam having an interiorly arranged spiral groove cut upon its inner face, means including a horizontally disposed, rotatable shaft passing entirely through said housing for operating said cam, a pin passing through each cylinder and slot, and a roller carried by each pin for engaging within said spiral groove for reciprocation of said cylinders.

2. An air pump comprising in combination, a horizontally arranged housing having a central cylinder casing, concentrically arranged cylinders each having a vertically arranged valved inlet and a horizontally arranged valved outlet at the same end thereof, each valved inlet being disposed at right angles to the horizontal axis of a cylinder having an elongated horizontally arranged slot at the other end, a piston within each cylinder, a hollow cam operative for rotation around said cylinders said cam having an interiorly arranged spiral groove cut upon its inner face, means including a horizontally disposed, rotatable shaft passing entirely through said housing for operating said cam, a pin passing through each cylinder and slot, and a roller carried by each pin for engaging within said spiral groove for reciprocation of said cylinders.

3. An air pump comprising in combination, a horizontally arranged housing having a central cylinder casing, concentrically arranged cylinders each having a vertically arranged valved inlet and a horizontally arranged valved outlet at the same end thereof and having an elongated horizontally arranged slot at the other end, a piston within each cylinder, an annular chamber arranged at the discharge end of said housing for direct reception of air as compressed in all of said

cylinders said chamber having a single vertical outlet, a hollow cam operative for rotation around said cylinders, said cam having an interiorly arranged spiral groove cut 5 upon its inner face, means including a horizontally disposed, rotatable shaft passing entirely through said housing for operating said cam, a pin passing through each cylinder and slot, and a roller carried by each 10 pin for engaging within said spiral groove for reciprocation of said cylinders.

4. An air pump comprising in combination a horizontally arranged housing having a central cylinder casing, a horizontally 15 arranged shaft passing entirely through said housing, concentrically arranged cylin-

ders each having a valved vertical inlet and a valved horizontal outlet at the same end thereof and having an elongated slot paralleling said shaft at the other end, a piston 20 within each cylinder, a hollow cam fixed to said shaft at one end said cam having a cam groove upon its inner face operative for rotation around said cylinders, means including a roller for cooperatively engaging said cam groove passing through the cylinder slots and connecting with the cam interior for reciprocation of said cylinders, and an air outlet arranged at the same end of the pump as its intake and paralleling 25 said intake.

FREDERICK C. FROELICH.
